UNITED STATES PATENT OFFICE.

BENJAMIN F. CALDWELL AND WILLIAM F. PETERSON, OF WHEELING,
WEST VIRGINIA.

METHOD OF PACKING SHEET-METAL ROOFING.

SPECIFICATION forming part of Letters Patent No. 341,314, dated May 4, 1886.

Application filed December 3, 1885. Serial No. 184,633. (No model.)

To all whom it may concern:

Be it known that we, BENJAMIN F. CALDWELL and WILLIAM F. PETERSON, citizens of the United States, residing at Wheeling, in the county of Ohio and State of West Virginia, have invented new and useful Improvements in Methods of Packing Sheet-Metal Roofing, of which the following is a specification.

Our invention relates to an improvement in rolls for packing metallic roofing, the purpose thereof being to provide means whereby the necessary fixtures—such as caps, anchors, and tools—may be easily and safely stored with the roofing.

Our invention consists in the method of packing sheet-metal roofing and securing the necessary caps, anchors, and tools, hereinafter fully described, and definitely pointed out in the claims annexed to this specification.

Referring to the accompanying drawings, Figure 1 is an elevation of a spool used by us in practicing our invention. Fig. 2 is a perspective view showing the manner of packing the sheeting. Fig. 3 is a side elevation showing the method of packing, the sheet-roofing being shown in dotted lines. Fig. 4 is a sectional view showing a modification. Fig. 5 is an end view of the roll, showing a modified manner of closing the ends. Fig. 6 is a detail elevation showing a further modification.

In the said drawings, the reference-numeral 1 designates a spool, consisting of two heads or ends joined by a central shaft, 2, these parts being formed of any suitable material—such as wood.

In packing the sheet-roofing, the caps, &c., are fastened to the central shaft by simply winding a cord around them to hold them in place, and the anchors and tools may, if desired, be attached to the shaft in the same manner. The metal roofing is then wound upon the spool in such manner that it is supported wholly upon the heads or ends of the spool, leaving an interior open space between the heads, in which the articles above mentioned may be placed and secured.

In order to apply the roofing to the spool, the latter may be placed in a machine, if desired. In this manner both ends of the roll are securely closed, leaving an inner space

which may be used as a space for storing the smaller tools and articles used in applying the roofing.

It is evident that the heads or ends of the spool may be varied in form without departing from our invention. For example, they may be circular or polygonal, and in either case they will perform the function assigned them. Inasmuch, however, as the chief purpose of our invention is to close the ends of the roll to form an interior chamber for a storage receptacle, we propose to use, if desired, two heads or caps only, either connected with or disconnected from each other. This construction is shown in Fig. 4 and also in Fig. 5. In both figures the roofing is rolled up in the usual manner and supported on the heads or ends 1^a, the inner space being adapted to receive the caps and other articles placed loosely thereon. We may, however, attach the heads 1^a to each other by means of strips 1^b applied to their peripheries; but we do not limit our invention to the same or to any attachment whatever, the broad idea being to close the ends of the roll to form an interior space for storage of the articles mentioned.

It may be desirable to form the heads 1^a with notches 1^c, which, as shown in Fig. 5, receive the hooked end of the roofing-strip, and this form of construction may or may not be adopted whether the heads are connected or not.

What we claim is—

1. The herein-described method of packing sheet-metal roofing with its caps, anchors, &c., which consists in winding or rolling the metal roofing-sheets upon heads, between which the said caps, anchors, &c., have been previously placed, substantially as set forth.

2. The herein-described method of packing sheet-metal roofing with its accompaniments, which consists in winding or rolling the metal-sheets upon a spool, to which the caps, anchors, and tools have been previously attached, substantially as set forth.

3. The herein-described method of packing sheet-metal roofing with its accompaniments, which consists in attaching the bent end of the metal sheet to notches formed in heads or disks, and then winding said metal roofing on said heads, between which the smaller articles

have been previously placed, substantially as described.

4. The method herein set forth of packing sheet-metal roofing, together with the necessary caps, anchors, and tools, said method consisting in attaching the smaller articles to a central shaft of a spool having two ends or heads and then winding the roofing upon said ends or heads, whereby the ends of the roll are se-

curely closed and the interior space protected, substantially as described.

In testimony whereof we affix our signatures in presence of two witnesses.

BENJAMIN F. CALDWELL.

WILLIAM F. PETERSON.
